[57] CLAIM

The ornamental design for a seal-spool for container, as shown.

DESCRIPTION

FIG. 1 is a perspective view of a seal-spool embodying my new design, shown in open condition;

FIG. 2 is a perspective view thereof, as it might be located on the side of a container, and shown in sealed or closed condition;

FIG. 3 is a perspective view thereof, illustrating the seal-spool in unsealed and partially open or erected condition;

FIG. 4 is a top plan view of a blank of material from which the seal-spool may be formed; and,

FIG. 5 is a perspective view of the underside of the seal-spool, shown in sealed or closed condition.

The exemplary container shown in FIG. 2 is provided only for illustrative purposes, and forms no part of the present invention.
